UNITED STATES PATENT OFFICE.

JOHN A. PEER, OF PHILADELPHIA, PENNSYLVANIA, ASSIGNOR TO ARTHUR L. BLESSING, OF BALTIMORE, MARYLAND.

ARTIFICIAL LEG.

SPECIFICATION forming part of Letters Patent No. 694,325, dated February 25, 1902.

Application filed May 18, 1901. Serial No. 60,555. (No model.)

To all whom it may concern:

Be it known that I, JOHN A. PEER, a citizen of the United States, residing at Philadelphia, in the county of Philadelphia and State 5 of Pennsylvania, have invented certain new and useful Improvements in Artificial Legs; and I do hereby declare the following to be a full, clear, and exact description of the invention, such as will enable others skilled in 10 the art to which it appertains to make and use the same.

My invention consists in the novel features hereinafter described, reference being had to the accompanying drawings, which illustrate 15 one form in which I have contemplated embodying my invention, and the said invention is fully disclosed in the following description and claims.

Referring to the said drawings, Figure 1 represents 20 a perspective view of my improved artificial leg arranged for use with a member amputated above the knee. Fig. 2 is a vertical transverse sectional view of the same. Fig. 3 is a vertical longitudinal section of the 25 same. Fig. 4 is an enlarged vertical longitudinal section of the foot. Fig. 5 is a transverse section of the same on line 5-5 of Fig. 4. Fig. 6 represents a section on line 6-6 of Fig. 4. Fig. 7 is a view showing detached the parts 30 of the joint used for the ankle and toe portions of the foot. Fig. 8 is a detail sectional view of the upper portion of the leg, showing it arranged for use with a member amputated at or slightly below the knee. Fig. 9 is a section 35 view of a portion of the leg, showing it arranged for use with a member amputated at a point considerably below the knee. Figs. 10, 11, and 12 are detail views relating to the knee-joint or spring-hinge. Fig. 13 is a detail 40 view of a tool used for adjusting the said knee-joint. Figs. 14 and 15 are views of a crutch attachment which may be conveniently employed in connection with the leg to relieve the wounded parts from pressure in standing 45 or walking.

The object of my invention is to provide an artificial leg which will be capable of being used with any form of amputation by simple adjustment of the parts and which can be adjusted vertically to accommodate persons varying considerably in height, so that it will

be necessary to provide only a few sizes to accommodate all cases for which an artificial leg is required. My improved artificial leg is also constructed to give the greatest possible comfort to the wearer and to enable him to use the artificial member in exactly the same manner and with the same freedom and confidence that he would a natural member.

The leg consists of three parts—to wit, the upper or thigh section, the calf or lower section, and the foot-section. In the drawings, A represents the thigh-section, which comprises an outer vertical stiffening-bar a , an inner stiffening-bar a' , said bars being composed of wood or light metal, and the flexible side portions $a^2 a^3$, which are secured together along vertical edges at front and rear. The outer stiffening-bar a extends from the knee-joint to a point somewhat above the hip-joint 70 and is secured to the outside of one of the side portions a^2 , preferably by riveting, in such manner as to leave the inner face of said side portion (which is preferably formed of leather or other flexible material) perfectly 75 smooth. The bar a is also preferably incased by means of a strip a^4 , sewed or otherwise secured to the side piece a^2 , and the rivets which secure the bar a to the side piece may or may not extend through the strip 80 a^4 , as preferred. The side piece a^2 will be cut away from points adjacent to the top of the bar a down to the front and rear edges of said side piece, as shown, and it may also be provided with cut-out portions a^5 at the 85 upper part to make it cooler, as shown in the drawings. The inner stiffening-bar a' is secured to its adjacent side piece a^3 (of leather or other suitable flexible material) by riveting or otherwise and is covered by a strip a^6 90 like the other stiffening-bar. The inner bar a' is shorter than the outer bar, as it extends up along the inner surface of the thigh of the wearer. The front and rear edges of the flexible side portions $a^2 a^3$ are adjustably 95 united in any suitable manner, as by lacing, as shown in the drawing, although I do not limit myself to the use of lacing, as I may employ any equivalent construction. To the upper end of the outer bar a , which extends 100 upward beyond the inner bar, is secured a belt A' , (see Fig. 1,) which passes around the

body and secures the upper part of said side bar to the trunk of the wearer, thus giving him better control of the limb.

The outer stiffening-bar a is provided at 5 its upper end with a belt B , to be secured around the waist of the wearer. Each of the flexible side pieces $a^2 a^3$ is provided with two or more pairs of slots a^7 at different heights to receive the straps $c c$ of a sling C , provided with a cushion or pad upon which the stump of the leg (if a thigh amputation) can rest gently. The ends of straps $c c$ are passed through one pair of the slots a^7 in each side piece and secured by any desired means, such 15 as buckles a^8 , secured to the side pieces, one adjacent to each of said slots, as shown in the drawing.

The lower or calf section D of the leg is also provided with inner and outer stiffening-bars $d^1 d^2$, secured to flexible side pieces $d^2 d^3$ and covered by strips $d^4 d^5$ like those of the thigh-section, and the edges of the flexible side sections are adjustably secured at front and rear by lacings or otherwise. The side 20 portions $d^2 d^3$ are provided each with a pair of slots $d^7 d^8$ to receive the straps e of a ventilating stump-supporting sling E (see Fig. 9) when the leg is used with a member amputated considerably below the knee, said sling 25 comprising a curved or cup-shaped piece of leather provided with perforations therein. The straps $e e$ are passed through the slots $d^7 d^8$ and secured adjustably in any desired way, as to buckles $d^9 d^{10}$, secured to the side pieces adjacent to said slots.

The flexible side portions of the thigh and calf sections are cut away at front and rear adjacent to the knee-joint (hereinafter described) to facilitate the action of the knee-joint and also to allow a portion of the leg of the wearer below the knee-joint to project rearwardly if the leg is to be used in such manner. The calf-section is also preferably provided with a knee-pad F , secured to the 40 front side of the flexible portions $d^2 d^3$, preferably by means of a strap f , said pad having a flap f' , which extends down inside of the calf-section, as shown in Fig. 3.

The thigh and calf sections of the leg are 45 connected by two spring joint or hinge connections G , the construction of which is shown in detail in Figs. 10 and 11 and 12. Each of these joints comprises two circular hinge members $g g'$, each provided with a shank g^2 , which is riveted or otherwise secured to one of the side or stiffening bars, as shown in Fig. 2. The hinge member g consists of a circular plate provided with an annular flange g^3 , a pair of stop-lugs $g^4 g^4$, and a central aperture to receive a separate hub or boss g^5 , provided with a series of ratchet-teeth g^6 on its outer face and having a central recess g^7 within the same. The hinge member g' consists also of a circular plate provided with an annular flange g^8 , adapted to register with the flange g^3 of the other member, stop-lugs $g^9 g^9$,

a central boss g^{10} , adapted to fit into the recess g^7 of the boss g^5 , and a spring-pawl g^{11} , secured to the outer face of the plate and provided with a part projecting through an aperture in the plate in position to engage the ratchet-teeth g^6 on the hub or boss g^5 . 70

g^{12} represents a coiled spring inclosed between the two plates $g g'$, one end being secured to the plate g , as shown at g^{13} , Fig. 10, 75 the other end being secured to the hub or boss g^5 . When the parts are put together, they are secured in position by a screw g^{14} , passing through the hub or boss g^5 and engaging a threaded aperture in the boss g^{10} . The boss g^5 is provided with a flange g^{15} , which projects beyond the edges of the aperture in plate g , through which the boss passes, and the rear face of the boss is provided with slotted or recessed portions to receive an adjusting-tool 80 H , such as is shown in Fig. 13, provided with bifurcated arms $h h$ to engage the recesses in the boss and turn it so as to tighten the spring g^{12} . The pawl g^{11} engages the ratchet-teeth of the boss and holds it in its adjusted position. The stop-lugs of one plate engage those of the other plate when the parts are moved unto the positions shown in Figs. 1, 2, and 3, so as to prevent the knee-joint from bending rearward. The springs g^{12} of the knee-joints 90 can be adjusted accurately, so as to give the required pressure to throw the lower part of the leg forward in walking in the most natural manner, and the hinge-plates $g g'$ are each provided with a shoulder g^{16} , adjacent to the 95 attaching-shank, which shoulder bears against the edge of the other plate, so that when the parts of the leg are in line, as in standing still, all the weight is borne by these shoulders and the plates, and no weight is put upon the screw g^{14} or boss g^5 . Hence, there is no 100 tendency of the joints to get out of order or to yield under any strain that may be put upon them, the strain not coming at any time on the pivotal portions. 110

I also provide the thigh and calf portions of the leg adjacent to the knee-joints with removable and adjustable cross-bars K for holding the stiffening-bars at the required distance apart. These devices are exactly alike, 115 and a description of one will apply to the other. The cross-bar K comprises two threaded bolts $k k$, passing through the opposite side stiffening-bars and rigidly secured thereto by nuts $k' k'$ on the inner sides thereof, and 120 a central sleeve K^2 , provided with right and left hand interior threads, and a central flange k^3 , which is constructed to enable the sleeve to be rotated. In this instance the central flange is provided with a series of holes to receive a tool to enable the sleeve to be turned. By rotating this sleeve the side stiffening-bars can be adjusted to the desired distance 125 apart and held rigidly in the adjusted position. It will be obvious that these adjusting cross-bars are not required when the wearer's leg extends through the portions of the arti- 130

ficial leg where they are located, and in such case one or both of the cross-bars will be removed, as required.

The foot-section L of my improved artificial leg is shown in detail in Figs. 4, 5, 6, and 7 and is constructed as follows: l represents the ankle portion of the foot-section, which is preferably hollowed out at its upper end, as shown at l', and is provided on each side with a vertical slot l² and with lateral recesses l³ l⁴, extending from the top down to horizontal shoulders l⁴ l⁴. (See Figs. 1, 2, and 5.) The lower ends of the stiffening side bars d d' of the calf-section fit into said recesses and are secured to the foot-section by a bolt M, which passes through the slots l² l² and is provided with a suitable nut m. (See Figs. 2 and 5.) By this means the length of the leg can be adjusted a distance equal to the length of the slots l², and the necessity of having so many sizes of legs in stock is avoided, as a few sizes can be made to accommodate persons of all the varying heights. When the stiffening-bars are adjusted above the shoulders l⁴ l⁴, blocks l⁵ l⁵ will preferably be inserted between the end of said bars and the shoulders, as shown in Fig. 5.

The bottom part of the ankle-section l is provided with the front and rear beveled faces l⁶ l⁷ and a rear flange l⁸.

l⁹ represents the main foot-section, provided with a hollowed-out portion l¹⁰ at the top to receive the ankle-section and a hollowed-out portion l¹¹ on the under side. The rear part of the upper portion is made to fit within the flange l⁸. The two parts are connected by an improved ankle-joint of peculiar construction, the parts of which are shown in detail in Fig. 7. The joint comprises two plates N N, each provided with a hemispherical socket n, one of said plates being provided with a pair of rockers n' or lugs having rounded surfaces, adapted to engage recesses N² in the other plate. Between the two plates and engaging the sockets n n there is a ball n³, and a bolt n⁴ extends through the said plates and the ball n³ and holds the parts together, the bottom portions of the sockets n being slotted, as shown at n⁵, to allow the parts to rock freely. In applying this joint I fit one of the plates N to the ankle-piece l and the other to the footpiece l⁹, fitting them into suitable recesses, and in order to allow a small amount of play in the joint I apply a rubber washer n⁶, preferably backed by a metal washer n⁷, under the head and nut of the bolt n⁴, as shown in Fig. 4.

In order to hold the parts together and give the proper spring or yielding motion forward and backward to the ankle-joint, I provide the two jointed rods O O, connected to the ankle portion and extending through apertures in the foot portion l⁹ into the recess l¹¹, where they are provided with cushioning and retracting springs o o, which hold the foot portion normally in the proper relation to the

ankle portion and permit the necessary movements of the parts with respect to each other.

The front portion of the footpiece l⁹ is provided with a toepiece l¹², connected to the footpiece by a joint P, exactly similar to the ankle-joint previously described, and springs p p are interposed between the two parts in front of and in rear of the joint P to permit the toepiece to move with respect to the footpiece and to restore it to normal position in walking, thus rendering the use of the artificial leg easy and natural and obviating almost entirely the awkwardness usually accompanying the use of an artificial leg.

In Figs. 1, 2, and 3 I have shown the leg arranged to accommodate a limb amputated above the knee, the stump being supported by the sling C and the side portions of the thigh-section, which are laced around it. In order to give further support, especially in cases where the end of the mutilated member is tender, I provide a crutch-support Q, (shown in Figs. 1 and 15,) which is attached to the outer stiffening-bar A and is provided with a hinge-joint q at a point substantially opposite the hip-joint of the wearer, the upper end of the crutch-support being provided with a support q', adapted to rest under the armpit of the wearer, and thus enable a large portion of the weight to be taken off the injured leg. The upper portion of the crutch-support is preferably provided with a spring latch or pawl q², which engages a notch q³ in the other part adjacent to the hinge (see Fig. 14) and has a tendency to hold the parts locked when in vertical position to prevent them from buckling, while not interfering with the operation of the hinge in sitting down or bending the body. The pad F may be detached when the leg is used in this manner.

In Fig. 8 the leg is shown arranged for use with a limb amputated below the knee where it is desired to support the body partly from the knee. In this case the sling C is secured in the lower slots a⁷ a⁷ to serve as a support for the user's knee, the knee being further cushioned by the pad F. In this case the cross-bar K will be removed from the thigh-section A, as indicated in the drawing.

In Fig. 9 I have shown the device arranged for use with a limb amputated considerably below the knee. In this case the sling E is employed and both cross-bars K K are removed. The pad F protects the knee from chafing on the upper edges of the calf-section, and the flap f' protects the leg of the wearer from rubbing against the lacings at the front of the calf-section.

It will be seen that the leg can be used for any kind of an amputation, and by means of the adjustable connection between the calf-section and the foot one size of leg can be adjusted to accommodate persons varying considerably in height, so that only a few sizes of the leg need be manufactured or kept in stock to supply any usual demand.

In action the artificial limb is thoroughly under control and will act so nearly like a natural limb as to enable the wearer to walk easily and without apparent effort and to make any ordinary movements with precision.

What I claim, and desire to secure by Letters Patent, is—

1. An artificial leg, comprising among its members a thigh portion having side stiffening-bars, the outer bar being extended upwardly a greater distance than the inner bar, flexible side portions connected to said stiffening-bar, adjustable devices for connecting said side portions together and a belt secured 15 to said outer side bar adjacent to its upper end, substantially as described.

2. An artificial leg comprising among its members, the thigh-section, a calf-section, a hinge connection between the said sections, 20 a spring for said hinge connection and devices for adjusting the tension of said spring having a part extending to the exterior of said hinge connection adapted to be operated without separating the parts of said hinge connection, substantially as described.

3. An artificial leg comprising among its members, the thigh and calf sections, a hinge connection connecting said sections comprising two plates pivotally connected, and provided 30 with stops to prevent the hinge from opening rearward, a spring for said hinge connection, a rotatable adjusting device for said spring and devices for holding said rotatable device in its adjusted position, substantially 35 as described.

4. An artificial leg comprising among its members, the thigh and calf sections, hinge connections between said sections, each comprising a pair of plates, pivotally connected, 40 a rotatable part disposed concentrically with the pivot of said plates and provided with ratchet-teeth, a coiled spring between said plates, secured to one of said plates, and to 45 said rotatable part, and a pawl on the other plate engaging said ratchet-teeth, substantially as described.

5. An artificial leg comprising among its members the thigh and calf sections, a hinge connection between said sections consisting 50 of two plates, one secured to each section, each plate being provided with a part to engage a part of the other plate to limit the movement of the hinge in one direction, a rotatable hub passing through one of said plates 55 and provided outside the hinge with means for turning it, a spring secured at one end to one of said plates and at the other end to said hub, ratchet-teeth on said hub, a pawl secured to one of said plates and engaging said ratchet- 60 teeth, and a pivot passing through said hub, and holding said plates together, substantially as described.

6. An artificial leg comprising among its members the thigh and calf sections, separate 65 hinge connections between said sections located at the inner and outer sides thereof, said calf-section being provided with a cross-

bar adjacent to said hinge connections and means for adjusting said cross-bar longitudinally to regulate the width of said thigh-sections, substantially as described. 70

7. An artificial leg comprising among its members the thigh and calf sections, separate hinge connections between said sections located at the inner and outer sides thereof 75 said thigh and calf sections being each provided with a cross-bar, adjacent to said hinge connections, and means for adjusting each of said cross-bars longitudinally to regulate the width of said sections, to insure the proper 80 operation of said hinge connections, substantially as described.

8. An artificial leg comprising among its members, thigh and calf sections, each provided with lateral stiffening-bars, and flexible 85 side portions, hinge connections between the adjacent stiffening-bars of said sections, each section being provided with a removable, adjustable cross-bar engaging its stiffening-bars, adjacent to said hinge connections, substantially as described.

9. An artificial leg comprising among its members, thigh and calf sections, each provided with lateral stiffening-bars, and flexible side portions, hinge connections between the adjacent stiffening-bars of said sections, each section being provided with a removable and adjustable cross-bar, comprising threaded rods or bolts extending through opposite stiffening-bars, adjacent to said hinge connections, nuts on said rods or bolts for securing each to one of said bars, and a sleeve provided with right and left threaded apertures connecting said rods or bolts, substantially as described. 105

10. An artificial leg comprising among its members, the thigh-section and calf-section hinged together, each section being provided with a means for holding and vertically adjusting a leg-supporting sling, and a sling adapted to be secured to either section and vertically adjusted therein substantially as described.

11. An artificial leg comprising among its members, the thigh-section provided with lateral stiffening-bars, flexible side portions and a plurality of strap-securing devices in different vertical planes, of a sling provided with supporting-straps for engaging adjustably said strap-securing devices, to enable the 115 sling to be adjusted vertically, substantially as described.

12. An artificial leg comprising among its members the thigh-section composed of inner and outer side bars and flexible side portions 125 connected therewith, the outer side bar being extended upward beyond the inner side bar, means for adjustably securing said flexible side portions together, a belt secured to the upper end of said outer side bar, and a crutch-support pivotally connected to said outer side bar below its upper end, at a point substantially in line with the hip joint, substantially 130 as described.

13. An artificial leg comprising among its members, the thigh-section provided with lateral stiffening-bars, and flexible side portions, a crutch-support hinged to the outer of said 5 stiffening-bars at a point substantially in line with the hip-joint and a spring-pawl adapted to engage a recess in a part connected with said crutch-support to hold it in line with said stiffening-bar, substantially as described.
14. An artificial leg comprising among its members the thigh-section and calf-section each provided with lateral stiffening-bars, and flexible side portions secured thereto and adjustably connected to each other, hinge connections between adjacent stiffening-bars, a removable cross-bar, engaging the side bars of each section, devices on each section for holding and vertically adjusting a sling, and a sling adapted to be secured to either of said 15 sections, substantially as described.
15. An artificial leg comprising among its members, a thigh and calf sections, each provided with a pair of lateral stiffening-bars, and flexible side portions, of a foot-section 25 having the outer portion thereof provided with a vertically-disposed part adapted to extend up within the lower part of the calf-section and provided on each side with a vertical recess to receive the lower ends of the side bars of said calf portion and a detachable bolt passing through said stiffening-bars and said vertically-disposed part, and forming the sole connection between the foot-section and calf-section, substantially as de- 30
- 35 scribed.

16. An artificial leg comprising among its members thigh and calf sections each provided with a pair of lateral stiffening-bars, and flexible side portions, of a foot-section having the outer portion thereof provided 40 with a vertically-disposed part adapted to extend up within the lower part of the calf-section and provided on each side with a vertical recess to receive the lower ends of the side bars of said calf portion, the said vertically-disposed portion of the foot-section, and the contiguous portions of said side bars being provided with registering vertically-disposed slots, and a detachable bolt passing through said slots and forming the sole connection between the foot-section and calf-section, substantially as described. 45

17. An artificial leg comprising among its members, the foot-section provided with parts movable with respect to each other and a joint 55 connecting said parts including two plates, each provided with hemispherical sockets, the one plate being provided with rocker-lugs and the other with recesses to receive said lugs, a ball interposed between said plates and 60 engaging the hemispherical sockets thereof, and a bolt passing through slotted portions of said plates and through said ball, substantially as described.

In testimony whereof I affix my signature 65
in the presence of two witnesses.

JOHN A. PEER.
